(57) **CLAIM**

The ornamental design for a monitoring system, as shown and described.

DESCRIPTION

FIG. 1 is a top perspective view of a monitoring system in accordance with an embodiment of the present design; FIG. 2 is a front side view of the monitoring system of FIG. 1; FIG. 3 is a rear side view of the monitoring system of FIG. 1; FIG. 4 is a right side view of the monitoring system of FIG. 1; FIG. 5 is a left side view of the monitoring system of FIG. 1; FIG. 6 is a top plan view of the monitoring system of FIG. 1; and, FIG. 7 is a bottom plan view of the monitoring system of FIG. 1.

The broken lines shown in FIGS. 1-6 represent unclaimed portions of the monitoring system and form no part of the claimed design.
